UNITED STATES PATENT OFFICE.

ALEXANDER H. WOOD, OF PETROS, TENNESSEE.

RAILWAY-TIPPLE.

1,204,527.

Specification of Letters Patent.

Patented Nov. 14, 1916.

Application filed January 8, 1915. Serial No. 1,163.

To all whom it may concern:

Be it known that I, ALEXANDER H. Wood, a citizen of the United States, residing at Petros, in the county of Morgan and State 5 of Tennessee, have invented a new and useful Improvement in Railway-Tipples, of which the following is a specification, reference being had to the accompanying drawing.

10 My improvement relates particularly to mine car tipples which are constructed for rotation on an axis parallel or approximately parallel to the track on which cars are delivered to the tipple, whereby the cars 15 are turned sidewise far enough to discharge their contents by gravity.

The object of my invention is to provide such a tipple which may be cheaply constructed and which may be easily and economically operated and repaired, and which 20 comprises provision for controlling the car contents while the latter are being discharged, this being for the purpose of avoiding breakage of the material. Such feature 25 is specially desirable in the handling of coal. Practically all parts of the structure are formed of stock pieces of iron or steel readily obtainable and easily put into the structure.

30 In the accompanying drawings, Figure 1 is a side elevation of a structure embodying my improvement; Fig. 2 is a section on the line, 2—2, of Fig. 1; Figs. 3 and 4 are detail views.

35 Referring to said drawings, A is a stationary supporting structure on which wheels or rollers, B, are mounted on axles which are on two lines parallel to each other and to the tipple axis. On said wheels rests the cylindrical frame or turning portion, C, of the 40 tipple. Said turning frame or portion comprises ring-form ribs, 1, and longitudinal beam members, 2, uniting said ribs to form a cylindrical skeleton structure. The rings 45 are formed by bending railroad rails, of size suited to the required strength, into ring shape, the "head" being turned outward to rest on the wheels or rollers, B. The meeting ends of the rails are joined by tie-plates, 50 3, placed at each side of the rib over the joints formed by said ends and in the channels formed between the "head" and "foot" of the rail. Said plates are riveted or bolted to the rib.

55 The longitudinal beams or members, 2, are pieces of channel iron extending through the series of ribs and laid flatwise (with

their flanges turned toward the axis of the structure), against the inner face of each rib—the foot of the rail of which the rib is 60 formed—and bolted or riveted to said foot. Any desired number of these longitudinal members may be used to give the structure the needed rigidity.

In the lower portion of each ring (assuming that the frame is in its rest position) is a horizontal bridge piece, 4, which is composed of channel iron having its flanges directed downward. At each end, said bridge piece is flattened and curved upward to rest 70 flatwise on the foot of the rib and there secured by riveting or bolting. Said bridges form supports, corresponding to ties, for two track rails, 5, which are parallel to each other and to the frame axis and are suitably 75 secured to said bridge pieces, as by means of rivets or bolts. Said rails are spaced from each other according to the gage of the cars, D, which are to be emptied in the tipple. 80

E is a fixed track over which the cars, D, are brought into the turning frame, C, the rails of said track registering with the rails, 5, when the rotary frame, C, is in its normal or rest position. Said fixed track, E, may be 85 level or inclined, as may be required or permitted by the location. If the track descends as it approaches the tipple, the cars may be sent into the tipple by gravity and returned by means of a rope. 90

Outward from and above each end of each bridge piece is a lower bracket or chair, 6, composed of a piece of flat bar iron and having a horizontal portion and an approximately upright portion, forming a leg, and 95 having its ends bent to lie flatwise against the foot of the ring 1, and secured thereto by rivets or bolts. Above each such chair is an upper chair, 7, which is also composed of a piece of flat bar iron bent to form a horizontal portion and an upright portion, and having its upper end bent to lie flatwise against the adjacent beam, 2, and having its lower end bent horizontally to lie flatwise upon the horizontal portion of the lower 105 chair, 6, said ends being bolted or riveted to the parts against which they rest. Above each track rail, 5, a wheel guard rail, 8, is secured to the lower chairs, 6, parallel to said rails. Each such guard rail is an angle 110 bar of metal having one of its flanges directed horizontally toward the other of said guard rails and having its other flange directed downward and bearing against the up-

per portions of the upright members of the chairs, 6, and firmly secured thereto. Said wheel guard rails extend the entire length of the cylindrical structure, C, and are spaced 5 above the rails, 5, only high enough to allow easy passage of the wheels of the cars, D, the horizontal flange of each angle-bar forming a means for retaining the car against movement away from the rails, 5, and the upright flanges of said angle-bars forming means for restraining the car wheels from moving sidewise or transversely to the rails 5.

At each side of the space to be traversed 15 by the car, a car body guide rail, 9, is secured to the chairs, 7, said rail being a metal angle bar having one flange directed downward along the inner face of the upright portion of each chair and the other flange 20 extending outward over the upper face of the chair. Each of said bars is firmly secured to the chairs upon which it rests. The height of the upper chairs, 7, is made such as to bring the body guard rails, 9, opposite 25 the upper portion of the car, and the chairs at opposite sides of the ring are spaced from each other to so position the said guard rails as to merely allow easy passage of the car when the structure, C, stands in position 30 to place the car upright.

Two exteriorly channeled rings, 12, surround the group of longitudinal beams, 2. Each such ring has its flanges directed outward and has its web secured to the webs of 35 the beams. Said channeled rings are preferably placed in planes which are equidistant from the middle of the length of the cylindrical frame.

It is to be observed that all the parts thus 40 far mentioned are made of ordinary stock materials. This simplifies and cheapens the purchase of stock and also facilitates and cheapens the work of building and repairing, all of which can be done at a blacksmith shop.

When the structure is in its normal or 45 rest position (so that the rails, 5, 5, are in the lowest position), the cars are supported upon the rails, 5. When the cylindrical 50 frame is turned, the car body bears against the body guard rail, 9, at that side of the car, and the wheels at that side bear sidewise against the wheel guard rail at that side; and when the structure is turned suffi- 55 ciently to make the wheels tend to leave the rails, 5, the wheels will bear against the horizontal flanges of the guard rails, 8, whereby the car is efficiently engaged to 60 compel its remaining in the position it assumed relative to the rotary structure when the car enters said structure.

Above the upper chairs, 7, at the side of the rotary structure next the upper portion 65 of the chute is a discharge apron, 11, ex- tending the entire length of the rotary struc-

ture and having one edge joined to the adjacent body guard rail, 9, and having its other edge joined to the adjacent channel-beam, 2. Said apron, 11, is formed of sheet metal and is preferably curved as shown in 70 Fig. 2. When thus placed, the inner edge of said apron is opposite the upper edge of the car body.

A chute, F, is supported by the supporting structure, A, parallel to the axis of the 75 tipple and eccentric to said axis, the upper portion of said chute being substantially horizontally opposite said axis and close to the apron, 11, and the chute extending thence downward any distance beneath the rotary 80 frame, whereby the space between the rotary frame and the upper portion of the face of the chute is relatively small and gradually increases going downward. Said chute has a sheet-metal lining, 10, to afford durability 85 and smoothness.

When the rotary structure is turned clockwise, as shown in Fig. 2, the discharge apron, 11, sweeps downward with its outer edge close to the face of the chute, F, so 90 that little if any of the coal in the car can pass between said members. As the turning progresses and the apron, 11, moves farther downward, the distance between the apron and the chute, F, gradually increases, so 95 that by the time or soon after the car has been turned far enough to discharge all of its contents by gravity the opening between the apron and the chute is large 100 enough to allow the charge of coal to pass. There the course of the chute, F, approaches the horizontal sufficiently to prevent such rapid movement of the coal as might cause breaking of the lumps. Farther on, the slant of the chute may be adapted to restrain the movement of the coal to the desired extent. Thus the entire charge is kept under control to prevent breakage of the coal. At the same time there is no delay 105 through retarding the movement of the rotary frame.

The rotary frame is supported entirely on the rollers, B, and it is turned forward far enough to discharge the coal and then turned backward to the normal or rest position, the position in which the rails, 5, are in alinement with the rails of the fixed track, E.

The forward turning is by means of an 110 expansion cylinder, 14, having a piston, 15, on which is a pivoted yoke, 16. To each end of said yoke is secured one end of a rope or cable, 17, which extends over guide pulleys, 18, and, 19, and thence into and a few times around the channel rings, 12, and thence 115 downward and over guide pulleys, 20 and 21, and beneath a pulley, 22. From a hanger, 23, on said pulley a rope or chain, 24, extends downward and supports a counter-weight, 25. The rope, 17, extends around 120

the channel rings as often as deemed necessary to make such frictional engagement as will prevent slipping.

To stop the rotary frame in the position 5 of rest when the frame is being turned backward, a post, 26, is set on the structure, A, to engage an arm, 27, on the frame.

The counter-weight is sufficient to return 10 the rotary frame, including empty cars, into the normal position and so hold said frame after the fluid in the expansion chamber, 14, has been released. Steam or compressed air or other fluid under pressure is let into the expansion chamber through the inlet 15 pipe, 28, by opening a throttle valve, 29, for driving the piston downward to draw the rope, 17, in the direction for turning the rotary frame forward. Such movement may be limited by the limit placed on the 20 downward movement of the piston. After the discharge of the cars, the throttle valve is closed and the exhaust valve, 30, on a branch pipe, 31, is opened. Then the counter-weight will draw on the rope, from 25 its side of the cylindrical frame, sufficiently to slide the piston upward and drive the fluid outward through the exhaust branch, 31. The rapidity of such exhaust will determine the rapidity of the return of the 30 cylindrical frame to its normal position.

The operator may vary the rapidity of such exhaust by varying the opening of the exhaust valve, 30.

The expansion chamber and the pulley, 35 22, and the counter-weight are placed substantially in a plane cutting the tipple axis transversely at its middle, and the pulleys, 19, and the channel rings, 12, are placed in or near planes parallel to said middle plane 40 and located at some distance to each side of the latter, in order that the action of the ropes for the turning of the rotary frame will be distributed upon said frame, although only one expansion cylinder and 45 one counter-weight are used. This arrangement of the rope, 17, with the pulley, 22, and the counter-weight allows adjustment of the counter-weight upon the rope, whereby a self adjustment of the rope takes place 50 so that, although the engagement of the rope with the rotary structure is divided and separated; the strain is automatically equalized and so maintained by the counter-weight.

55 Obviously the tipple may be made of sufficient length to receive one or a group of cars at the same time.

I claim as my invention,

1. In a tipple, the combination of a 60 rotary frame, means external to the perimeter of said frame for supporting said frame rotatably, a rope extending around said frame in two planes which are transverse to

the tipple axis, said rope extending away from said frame at opposite sides of the 65 engagement with the frame, a counter-weight hung shiftably on said rope at one side of said frame, and means applied to said rope at the opposite side of said frame for drawing said rope toward said side in 70 opposition to the action of said counter-weight, substantially as described.

2. In a tipple, the combination of a cylindrical frame, means external to the perimeter of said frame for supporting the latter 75 rotatably, a counter-weight, a pulley connected with said counter-weight, an expansion member, a rope in operative relation with said expansion member and extending to and around said cylindrical frame in two 80 planes which are transverse to the tipple axis, and thence beneath said pulley, substantially as described.

3. In a tipple, the combination of a cylindrical frame, means external to the perimeter of said frame for supporting the latter 85 rotatably, a counter-weight, an expansion member, and tension means leading from said counter-weight and said expansion member to said frame at a plurality of 90 planes transverse to said frame and there engaging said frame, substantially as described.

4. In a tipple, the combination of a cylindrical frame, means external to the perimeter of said frame for supporting the latter 95 rotatably, a counter-weight, tension means leading from said counter-weight to said frame in a plurality of planes transverse to said frame and there engaging said frame, 100 and means under control of an operator for turning said frame in opposition to the action of said counter-weight, substantially as described.

5. In a rotary tipple, the combination of 105 a stationary structure, wheels supported by said structure on two lines parallel to the tipple axis, ring-form ribs resting on said wheels, longitudinal beams extending through said series of ring-form ribs and 110 secured thereto, two exteriorly-channeled rings surrounding said group of beams and secured thereto, tension means applied to said channel rings, a counter-weight shiftably supported by said tension means and 115 means for drawing said tension means, substantially as described.

In testimony whereof I have signed my name, in presence of two witnesses, this 17th day of December, in the year one thousand nine hundred and fourteen.

ALEXANDER H. WOOD.
